La Verne E. Clayton, Rockford, Ill. (½ Amerock Corporation, 4000 Auburn St., Rockford, Ill. 61101)

Original design application Aug. 12, 1970, Ser. No. 24,455. Divided and this application Mar. 25, 1971, Ser. No. 128,226

Term of patent 14 years

Int. Cl. D8—09

U.S. Cl. D8—179

FIG. 1

FIG. 2

FIG. 4

FIG. 3

FIG. 1 is a front view of an escutcheon plate for a pull showing my new design.

FIG. 2 is a side view as seen from the bottom of FIG. 1.

FIG. 3 is an end view as seen from the left of FIG. 1.

FIG. 4 is an enlarged fragmentary sectional view taken along the line 4—4 in FIG. 1.

This application is a division of my copending application Ser. No. D. 24,455, filed Aug. 12, 1970, Pat. No. D. 222,233, Oct. 12, 1971.

I claim:

The ornamental design for an escutcheon plate for a pull, as shown.
